[57] CLAIM

The ornamental design for a flexible game board, as shown and described.

DESCRIPTION

FIG. 1 is a perspective view of the top of my flexible game board showing my new design;

FIG. 2 is a side elevational view thereof;

FIG. 3 is a bottom plan view thereof;

FIG. 4 is an end view thereof from the left as viewed in FIG. 2; and

FIG. 5 is a perspective view of my flexible game board, rolled up.

Fig. 3
